UNITED STATES PATENT OFFICE.

CHARLES M. HALL, OF NIAGARA FALLS, NEW YORK.

EXPLOSIVE COMPOUND.

SPECIFICATION forming part of Letters Patent No. 763,666, dated June 28, 1904.

Application filed September 5, 1903. Serial No. 172,132. (No specimens.)

To all whom it may concern:

Be it known that I, CHARLES MARTIN HALL, of Niagara Falls, in the county of Niagara and State of New York, have invented a new and useful Explosive Compound, of which the following is a full, clear, and exact description.

My invention consists of an explosive compound composed of silicon combined with an oxidizing agent. When silicon, either pure or alloyed with other elements, is oxidized to silica, a very large amount of heat is evolved. The best way of utilizing this energy in an explosive compound is to mix the silicon with nitrate of ammonium. The silicon, either pure or in alloy with other elements, should be finely powdered and mixed with nitrate of ammonium in such proportions that one-third of the oxygen in the nitrate of ammonium will oxidize the silicon to silica, the remainder of the nitrate of ammonium being resolved by the explosion into free nitrogen and steam in equal volumes. Suitable proportions are fifteen per cent. of powdered silicon and eighty-five per cent. of nitrate of ammonium.

Instead of nitrate of ammonium other oxidizing agents or mixtures of the same—as, for instance, chlorate of potash or picric acid—may be used. If chlorate of potash is employed, it is well to use it in excess above the proportion required merely to oxidize the silicon, as in such cases a considerable proportion

of free oxygen is given off at a very high temperature.

The silicon which I use is best made by heating silica in excess with carbon in the electric furnace or by heating carborundum in the same way with an excess of silica.

Instead of using silicon I may use an alloy of silicon and iron or other heavy metal—as, for instance, an alloy containing fifty per cent. of silicon and fifty per cent. of iron or sixty per cent. of silicon and forty per cent. of iron. Such alloys may be cheaply prepared and are readily pulverized.

In firing the mixture fulminating agents are employed.

The silicon which I used is unoxidized—*i.e.*, it is still capable of combining with oxygen—and I do not claim the use of silica, which has been used as an inert carrier or absorbent for nitroglycerin.

I claim—

An explosive compound containing silicon in an oxidizable condition and an oxidizing agent; substantially as described.

In testimony whereof I have hereunto set my hand.

CHARLES M. HALL.
